INVENTOR:

Hans Nagel.

UNITED STATES PATENT OFFICE.

HANS NAGEL, OF BROOKLYN, NEW YORK, ASSIGNOR TO PALM, FECHTELER & CO., OF NEW YORK, N. Y., A CORPORATION OF NEW YORK.

DESIGN FOR A PLATE OR SIMILAR ARTICLE.

49,438.

Specification for Design.

Patented July 25, 1916.

Application filed June 6, 1916. Serial No. 102,098. Term of patent 3½ years.

To all whom it may concern:

Be it known that I, HANS NAGEL, a citizen of the United States, residing at Brooklyn, in the county of Kings and State of New York, have invented a new, original, and ornamental Design for a Plate or Similar Article, of which the following is a specification, reference being had to the accompanying drawing, forming part thereof.

The figure is a plan view of a plate showing my new design.

I claim:—

The ornamental design for a plate or similar article as shown.

HANS NAGEL.
